(57) **CLAIM**

The ornamental design for a coin sorter as shown and described.

DESCRIPTION

FIG. 1 is a perspective view of a coin sorter, showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged portion view labeled, "9", in FIG. 1; and,

FIG. 10 is an enlarged portion view labeled, "10", in FIG. 2. The even dashed broken lines depict portions of the coin sorter that form no part of the claimed design. The dot-dashed lines represent the boundaries of the enlarged portion views of FIGS. 9 and 10 in FIGS. 1, 2, 9 and 10 and form no part of the claimed design.

1 Claim, 10 Drawing Sheets
